UNITED STATES PATENT OFFICE.

CARL WUNDERLICH, OF SCHIRNDING, GERMANY.

SHEARING AND PUNCHING MACHINE.

SPECIFICATION forming part of Letters Patent No. 779,387, dated January 3, 1905.

Application filed February 28, 1904. Serial No. 194,792.

To all whom it may concern:

Be it known that I, CARL WUNDERLICH, a subject of the German Emperor, residing at Schirnding, Upper Franconia, in the German Empire, have invented new and useful Improvements in Shearing and Punching Machines, of which the following is a specification.

My invention relates to a beam shearing and punching machine designed to consume less power than other machines of this class. In contradistinction to prior shearing and punching machines worked by direct eccentric-pressure rigid connections are avoided, whereby fractures and other defects on breakdown are obviated.

To secure the objects in view, I employ elastic members to connect one end of the beam with the eccentric on the main shaft—that is to say, to hold the pressing-surface of the eccentric against a roller mounted in the one beam end, and like elastic members to hold the other beam end against the shear-slide or punch-piston, a spring-controlled dog or block being, moreover, inserted between the beam end and the semispherical pressing-block of the slide or piston. On a breakdown—such as fracture of the shears, jamming of parts, &c.—occurring the resistance offered to further up-and-down motion of the beam is without effect on the holding means of the slide or piston, owing to the resilience of the said elastic members and to the dog being brought out of action by its spring.

My invention is shown in the accompanying drawings, in which—

Figure 1 shows an elevation of the top portion of a shearing-machine, a part of the shear-slide being broken away to display underlying parts. Fig. 1^a is a sectional view illustrating the application of a punching device to the machine. Fig. 2 is a vertical section illustrating, on a larger scale, the method of connecting the beam and the shear-slide. Fig. 3 is an elevation, partly in section, showing, on a larger scale, the dog mechanism and coöperating parts. Figs. 4 and 5 show details of the roller end of the beam.

a is the main shaft of the machine, which may be driven from shafting or by an elec-

tric or other motor direct-coupled, if desired. On the shaft *a* is mounted the eccentric *b*, which in rotating bears against the steel roller, mounted in the end *d'* of the beam or lever *d*, whereby up-and-down motion is imparted to the latter. As the eccentric *b* does not act directly upon the beam end *d'*, the great friction at the surface of pressure, which forms an objectionable feature in prior machines of this class, is avoided, for by the insertion of the roller *C* the friction is reduced to a minimum, being practically limited to a single line, so that much less power is required than is usually the case for machines of the same output. The roller is mounted in a bearing open below and is retained in position by means of the cheek-plates *n*. Should a breakdown occur—for instance, jamming of the shear-slide in its lower position—the beam end *d'*, remaining in its elevated position, will compress the spring *m*, but will not cause fracture or disturbance of any machine part. On the beam *d* turning on its fulcrum *B* the bell-crank lever *o*, loaded with the counter-weight *o'*, is caused to take up the position shown in Figs. 1 and 3 and will butt against the casing *p*, rigidly secured by means of a screw-pin *p'* to the dog or block *k* and containing a spring coiled round the said pin *p'*. The spring will thus be compressed and the dog *k* forced between the beam end *d'* and the press-block *l*. The latter is of substantially semispherical form in order that it may adapt itself to the position of the beam *d* bearing upon it, which beam, owing to its motion about the fulcrum *B*, does not descend in a strictly-vertical path upon the block *l*. The motion of the beam *d* will thus be directly transmitted to the shear-slide *r* or punch-piston *r'*, which, according to the stroke of the beam, will descend upon the work and effect shearing or punching, as the case may be. On the upward stroke of the beam end *d'* the highest position of the slide *r* and piston *r'* is regulated by means of the stop *r''*. If at any time the part *r* or *r'* is to be brought out of action, the bell-crank lever *o* must be turned into the broken-line position, Fig. 1. By reason of the counter-pressure of the spiral spring the dog then snaps back, so that on de-

scent of the end d^2 again there is no pressure exerted by d^2 on l , owing to the gap between them. Since the spring m' expands on the downward non-working stroke of the beam 5 end d^2 , the part r or r' is always maintained in the highest position. Thus material to be sheared or punched can be introduced into the machine without any inconvenience.

Having thus described my invention, what 10 I claim as new, and desire to secure by Letters Patent of the United States, is—

1. In a shearing and punching machine, a rocking beam, an eccentric-shaft, an eccentric on said shaft coöperating with one beam end, 15 a spring-actuated device connecting said beam end and eccentric, a tool-slide at the opposite beam end, a spring-actuated device connecting the latter and the slide, a sliding, spring-controlled dog secured to the second 20 said beam end, and means for forcing the said dog between the beam end and the slide, substantially as described.

2. In a shearing and punching machine, a 25 rocking beam, an eccentric-shaft, an eccentric on said shaft coöperating with one beam end, a spring-actuated device connecting said beam end and eccentric, a tool-slide at the opposite beam end, a spring-actuated device connect-

ing the latter and the slide, a sliding, spring-controlled dog secured to the second said 30 beam end, and a counterweighted bell-crank lever pivoted to the last said beam end and forcing said dog between the latter and the slide, substantially as described.

3. In a shearing and punching machine, a 35 rocking beam, a friction-roller mounted at one end, an eccentric-shaft, an eccentric on said shaft coöperating with said roller, a spring-actuated device connecting said beam end and eccentric, a tool-slide at the opposite beam 40 end, a spring-actuated device connecting the latter and the slide, a semispherical press-block located at the top of the slide, a sliding, spring-controlled dog secured to the second 45 said beam end, and a counterweighted bell-crank lever pivoted to the last said beam end and forcing the said dog between the latter and the slide press-block, substantially as described.

In testimony that I claim the foregoing as 50 my invention I have signed my name in presence of two subscribing witnesses.
